UNITED STATES PATENT OFFICE.

EDWARD E. TALIAFERRO, OF CHATTANOOGA, TENNESSEE.

SPRING TALKING-MACHINE MOTOR.

Application filed July 8, 1920. Serial No. 394,659.

To all whom it may concern:

Be it known that I, EDWARD E. TALIAFERRO, a citizen of the United States, residing at Chattanooga, in the county of Hamilton and State of Tennessee, have invented certain new and useful Improvements in Spring Talking-Machine Motors; and I do hereby declare the following to be a full, clear, and exact description of the same, reference being had to the accompanying drawings, forming part of this specification.

This invention relates to spring motors and has for its particular object the provision of such a motor for use with a constant speed mechanism, such for example as a talking machine.

The object of the present invention is to provide a smoothly running driving mechanism for rotating the turntable of a talking machine or a similar object.

A further object of the invention is to provide a spring motor of large diameter for use with a talking machine.

25 A still further object of the invention is to provide mechanism so arranged that when the main spring of the talking machine motor breaks there will be no stripping of gears as is now the custom.

30 In the usual form of talking machine the turntable is driven from the spring motor by means of a positive line of gears, the main driving gear usually being an integral part of the spring motor itself and the 35 worm being driven directly by the barrel so that the worm is vertically arranged in the talking machine box. This universally adopted arrangement precludes the use of a large barrel for carrying the main spring

40 since the motor must be over the horn in the cabinet type machines. The disadvantage of the position of the vertically arranged springs in the usual type of motor is lessened by providing a plurality of coils all

45 cooperating together in such a manner that each of the springs tends to wind the casing on the next higher spring. It is of course well-known to all, that a single spring would be much more satisfactory

50 than this plurality of coils, but so far it has been impossible to arrange the mechanism in the box to permit the use of a barrel of large diameter. In the present invention a radical departure has been made and the 55 spring has been placed in a horizontal position which will permit the barrel to be

as large as the turntable itself, so that a single coil spring may be used. The use of this large spring requires that the large driving gear should be stationary and that the coil spring barrel should revolve. The means whereby this is carried out is described and further explained later in the specification at the proper place.

60 In talking machine motors as at present constituted the spring necessarily has a heavy tension and since the large gear is an integral part of the barrel there is a constant pressure on the teeth of the worm, 65 the drive being direct. When the motor spring breaks there is a violent reaction in a direction opposite to the normal direction of drive, and since the teeth of the gear and of the worm cannot be made strong 70 enough to take care of this heavy reaction, the usual result of a broken spring is a 75 number of stripped teeth. In the motor here shown all danger of stripping of teeth has been obviated by the provision of 80 a safety pinion which screws on the large drive gear in one direction of drive but leaves this wheel free to turn in the opposite or non-driving direction by virtue of its threaded connection, so that when the 85 heavy impulse due to a broken spring is transmitted by the shaft to the large gear, the large gear simply moves freely on its threads so that neither the teeth of the worm, nor the teeth on the center gear are 90 damaged. It might be remarked here that the use of such a safety pinion in watches was the main feature which aided in the supplanting of the Swiss watches by the American made product, but no attempt 95 has so far been made to introduce a pinion of this nature into a talking machine motor, undoubtedly due to the fact that the inventors and mechanics were unable to find a suitable place to provide such a pinion.

100 In the drawings:

Figure 1 is a plan view of my device, showing the turntable periphery in dotted lines to indicate its relative size.

Figure 2 is a central vertical section taken 105 through the winding device.

In the drawings, 10 represents the base formed by the top or upper wall of the horn chamber of a talking machine cabinet, and 11 represents the central post secured 110 thereto by means of a nut 12 or other suitable fastening device. The central post 11

is reduced at its upper portion to form a shaft 13 and provides a shoulder 14 between these parts. A sleeve 15 is mounted on the shaft 13 and carries at its lower end a bevel pinion 16 preferably threaded thereto, as indicated at 17, and meshing with a similar gear 18, secured to one end of a winding arbor 19 passing through a central bore 20 in the lower portion of the central post 11, 10 and being provided as is customary with a small integral collar 21 and an adjustable washer 22 in order to correctly position the gear 18 for engagement with the driven gear 16.

15 The central shaft 13 has a reduced threaded end 26 providing a shoulder 27 against which the annular threaded sleeve 28 of the main gear 29 is adapted to abut during normal operation of the machine. At its 20 upper portion the central shaft 13 is provided with the usual pin 30 which may have the reduced guiding nipple 31 for centering and guiding the record blank. The turntable 33 is of the usual type having a downwardly extending toothed flange 34 fitting into a recess 35 in the turntable pulley 37 which loosely embraces the pin 30 and rests on the shoulder 38 formed on the central post, all parts of which, as will be understood, are stationary at all times.

30 The barrel 40 is loosely mounted on the sleeve 15 and is closed by a cap 41 at its lower side. The spring 42 is provided with the usual end links 43, one of which is 35 fastened to the button or hook 44 on the downturned integral flange 45 of the barrel, and the other of which is secured to the similar hook 46 on the sleeve 15. To wind the device, a winding crank 47 is screwed 40 into the connection 48 with the winding arbor 19 and the sleeve 15 is rotated to wind the spring through the gears 18 and 16, reverse movement of the sleeve 15 being prevented by means of the ratchet 49, as 45 is customary.

45 A pair of spur shafts 50 are threaded into the circular upper face 51 of the barrel as at 52 and are each provided at its point of connection with a small collar 53 to support 50 an idle pulley 54 and each of these shafts 50 also carries a similar pulley 55 at its upper reduced end, it being understood that these pulleys 54 and 55 are freely movable on the shaft 50, but that the shaft 50 itself is constrained to move with the barrel as the latter revolves.

55 The upper face 51 of the barrel also supports a governing mechanism 60 adjustably secured in brackets 61 so arranged that the 60 governor worm 62 may be in proper mesh with the cooperating wheel 63 on the drive shaft 64 which revolves in brackets 65 and 66, the latter carrying an adjustable thrust bearing 67 to permit adjustment of the wheel 65 63 with respect to the driven worm 62 on

the governor shaft. The shaft 64 is provided centrally with a spiral thread and at the end nearest the bracket 65 carries a fixed drive pulley 69. An idle pulley 70 is mounted in a yoke 71 secured to a post 72 by a 70 spring 73 of sufficient strength to keep taut the endless cable connection 74, this cable passing in turn from the driving pulley 69 about one of the idle pulleys 55 at the top of the shaft 50, thence to the turntable pulley 75 37, then about the other pulley 55 and from there to the idle pulley 70 which guides the endless cable back to the driving pulley 69 by way of the two lower idle pulleys 54.

75 It will be noted that during the winding 80 operation the only parts that move are: the sleeve 15; the bevel gears 18 and 16, the latter fast to the sleeve 15; and the arbor, which is fast to the gear 18. During the running of the machine all of these parts 85 are stationary, as is the central shaft 13 and the main gear 29; the movable parts being the barrel and the parts mounted on its upper surface 51. In case of the spring 90 breaking the gear 29 will rise vertically on backward impulse, thereby avoiding all harm to the machine.

95 What I claim is:

1. In a spring motor device, a stationary central shaft, a spring coiled about said central shaft, a disc connected to said spring and movable about said central shaft, and means carried by said disc for transmitting rotary motion to a member revolving in a plane perpendicular to said shaft. 100

2. In a spring talking machine motor, a stationary shaft, a turntable rotatable thereon, a coil spring concentric with said shaft, and means connecting said spring and said turntable for driving the latter. 105

3. In a spring motor, a central shaft, a member rotatable on said shaft, a spring surrounding said shaft, a casing for said spring and secured thereto, a stationary gear on said central shaft, a pulley on said shaft connected with said first mentioned rotatable member, and means for connecting said pulley and said gear for driving said member. 110

4. In a spring motor, a stationary central shaft, a sleeve on said shaft, a housing rotatable on said sleeve, a spring coiled about said sleeve and connected thereto at one end and to said housing at the other end, a stationary gear on said first mentioned shaft, a pulley loosely mounted on said shaft, and means carried by said housing operatively connecting said gear and said pulley, whereby the latter is revolved on said central shaft. 115 120

5. In a spring motor for driving a talking machine turntable, a stationary central shaft for guiding said turntable, operative means for driving said turntable, said means including a single coil spring surrounding said shaft and positioned parallel to said turntable. 125 130

6. In a talking machine, a central shaft, a turntable rotatable about said shaft, a spring coiled about said shaft in a position parallel to said turntable, and means for 5 operatively connecting said spring and said turntable.
7. In a talking machine, a central shaft, a member rotatably mounted on said shaft, a turntable also mounted on said shaft, and 10 driving means mounted in part on said rotatable member for driving said turntable, and means for causing relative movement between said rotatable member and said turntable.
- 15 8. In a talking machine, a central shaft having a threaded intermediate section forming a shoulder with the main section, a gear stationary in its normal operation but loosely threaded on said intermediate section 20 and normally resting on said shoulder.
9. In a talking machine, a turntable adapted to support a phonograph disc, a spring motor, a safety gear, mechanism connecting said motor to said turntable through said 25 safety gear and operating to rotate the latter.
10. In a spring motor, a support, a stationary gear carried thereby, a plurality of rotatable members coaxial therewith, and 30 means rotatable about said support and co- operating with said gear to transmit rotary movement from one to the other of said members.
11. In a spring motor, a stationary shaft, a gear secured thereto, a spring, a member 35 rotatable about said shaft and means including a member meshing with said gear, for transmitting rotary movement from said spring to said first-mentioned member.
12. In a spring motor, a stationary gear, 40 a spring, a rotatable driven member, means for winding said spring, power transmitting means connecting said spring and said driven member, and a central shaft furnishing sole support and guide for all of said mechanism. 45
13. In a spring motor, a stationary shaft, a spring surrounding said shaft, a disk connected to one end of said spring, a member rotatable on said shaft, and means including 50 mechanism mounted on said disk and rotatable about said shaft for transmitting motion from said spring to said member.
14. In a spring motor, a support, a stationary gear carried thereby, a rotatable 55 member mounted coaxially with said gear, and a worm rotatably mounted on said member and meshing with said gear.

EDWARD E. TALIAFERRO.
